UNITED STATES PATENT OFFICE

2,451,560

FLUID OPERATED PUMP FOR OIL WELLS
AND THE LIKE

Robert B. Knowles, Maywood, Calif.

Application March 15, 1946, Serial No. 654,661

8 Claims. (Cl. 103—46)

1

This invention relates to pumps of the character particularly designed for use in the oil well industry, in which operation of the pump is effected by the admission of a fluid intermittently under pressure to the pump actuating mechanism, and is particularly designed to provide an improved construction over that shown in U. S. Patent No. 2,342,855.

Prior art pumps in use at the present time provide very little space for the working parts and are relatively complicated and delicate, causing considerable loss of time and expense for proper maintenance.

As used in the oil well industry, pumps may be situated thousands of feet below the surface of the ground and it is very desirable that the construction of the pump should be as simple as possible in order to provide adequate space for the arrangement of parts of sufficient ruggedness to operate successfully under very heavy loads.

It is an object of the present invention to provide pump operating mechanism of simple construction in order to provide adequate space for the working parts of the mechanism.

Another object of the invention is to provide fluid operated pump mechanism permitting of ready adaptation to particular working conditions.

A still further object of the invention is to provide a fluid operated pump mechanism in which the usual provision of "macaroni" or small diameter tubing leading from the ground surface to the operating mechanism may be dispensed with.

Further objects and features of the invention will appear from the following description taken in conjunction with the accompanying drawings, in which:

Fig. 1 is a vertical section through the lower portion of the pump actuating mechanism which has been broken into two views;

Fig. 2 is a vertical section through the upper portion of the pump actuating means, the mechanisms in Figs. 1 and 2 being shown in the position of the parts when nearing the end of the lifting or pumping stroke;

Fig. 3 is a vertical section through a special packer drawn to a larger scale than Figs. 1 and 2, connected in a tube extending to the surface of the ground;

Fig. 4 is an elevation partly in section of a standard packer positioned below the special packer of my invention, drawn on a smaller scale;

Fig. 5 is a vertical section, to a larger scale, through a plate valve;

2

Fig. 6 is a plan view of the plate valve shown in Fig. 5;

Fig. 7 is a section on line 7—7 of Fig. 1, drawn on a larger scale; and

Fig. 8 is a schematic diagram showing the relative positions of the various components of the pump in assembled relation in a well.

Referring to the drawings, the numeral 10 in Figs. 1 and 2 indicates the barrel containing the pump operating mechanism and which is suspended in the well casing 12 by a tube 24 screwed to union 28 and extending upwardly through a standard packer 13 engaging with the well casing (Fig. 4) and serving to carry the weight of the barrel. Tube 24 actually is composed of a plurality of different sections jointed together but for clearness is referred to as one length of tube, extending from the barrel 10 to the surface of the ground. Tube 24 continues upwardly from the standard packer 13 through special packer 14 contained within the tube 24 and positioned by a supporting ring 22 held between lengths of tube 24, at a joint 16.

At the surface of the ground, tube 24 is connected to any appropriate mechanism supplying fluid, either liquid or gaseous, under intermittent pressure, to the operating mechanism in the barrel 10 through the tube. Operating fluid is directed by the special packer 14 into an inner

tube 54 mounted within tube 24 and extending within that tube to mechanism within barrel 10. The special packer acts to seal the top of the inner tube 54 to tube 24 by packing 30 arranged between tube 54 and a sleeve 32 screwing into the ring 22 and threaded at its lower end to receive a packer tightener sleeve 36, a follower ring 38 being supported on the tightener sleeve. The tightener sleeve 36 projects sufficiently below the end of sleeve 32 to enable it to be gripped by the usual pipe wrenches and is screwed into the sleeve to compress the packing, which may be of the chevron type, between the follower ring 38 and a ring 34 acting as a lower abutment for a spring 42, the upper end of which abuts against the ring

22. The purpose of this spring is to facilitate loosening of the packing when releasing the grip of the special packer on the tube 54.

Standard packer 13 is modified by the provision of outlets 15 in the union 52 leading from between tubes 24 and 54 into the space between the upper end of the packer 13 and the inside of the well casing through which space oil and exhaust working fluid flow upwardly and out of the well. The packer 13 comprises the usual rubber packing rings 13a, slips 13b working against cone slip

seat 13c, slip setting springs 13d and spring locking sleeve 13e.

The barrel 10 is formed as a cylinder having an inwardly tapered upper end 26 which is secured to the lower end of tube 24 by coupling 28. The barrel is divided into an upper compartment 29 and lower compartment 31 by means of a partition 58 secured, as by welding, to the inner surface of the barrel and provided with a series of bores 57 controlled by a plate valve generally indicated by 59, and more fully described herein after.

An upstanding tubular member 56 is screwed into a threaded bore in the plate or partition 58, the upper end of the tubular member being connected to the lower end of the tube 54. Below partition 58, an operating piston 60 is positioned and is provided with an upwardly extending tube 62 passing into the tubular member 56. Tube 62 passes at its upper end through a head 64 secured thereon which has a pressure-tight sliding fit within the cylindrical member 56, this construction affording a telescopic joint through which the working fluid flows.

A passage 66 is provided through the operating piston 60 communicating at its upper end with the bore of the tube 62, and with the lower surface of the piston 60 at its lower end. A plurality of valves 68 are arranged in bores 69 extending vertically through the operating piston.

The valves are formed, in the illustrated embodiment of the invention, with stems 70 and and mushroom heads 71. The upper end of the bores are threaded and plugs 72 are screwed therein. Compression springs 76 are arranged between the abutments 74 pinned to the valve stems and the plugs 72. Conduits 78 are arranged to extend between the valve seats and the upper surface of the operating piston 60. The operation of the valves will be later described.

A piston rod 80 is screwed at its upper end into the piston 60 and extends downwardly through a spider 82, having passages 84 therethrough, arranged toward the lower end of the barrel 10, and is connected to the piston 96 of the usual reciprocated plunger type pump, which obviously may be substituted by any other type of plunger pump. The lower end of the pump barrel 94 is fitted with a standing valve 98, while a traveling valve 100 (Fig. 7) is arranged at the lower end of the piston rod to enable oil in the pump barrel to flow through a bore 102a in the lower end of the piston rod past the valve 100 and outwardly above the upper face of the pump piston 96 through openings 102.

The weight of the moving parts, in mechanism operating deep well pumps, may be sufficient to cause the piston 60 and pump piston 96 to settle with sufficient speed to the bottom of its stroke when the working fluid is relieved of pressure, but in order to secure a rapid back-down of these parts in the case of shallow wells, I may utilize a compression spring 88 (Fig. 1) arranged between the lower surface of the spider 82 and an abutment 90 pinned to the valve rod 80.

A length of relatively light spring 86 is seated on the upper surface of the spider 82 in position to engage against the mushroom heads 71 of the valves 68 toward the end of the downward movement of the piston 60 and insure the positive closing of the valves.

The plate valve means used to assure one-way upward flow of the oil through the holes 57 in partition 58 is preferably formed as a sleeve surrounding said tubular member having a wash-

erlike face, as fully shown in Figs. 5 and 6 and generally indicated at 59 in Fig. 2. The valve comprises a washerlike lower face 106 providing a tapered valve seat engaging face 107, and a vertical sleeve 108 surrounding the upstanding tubular member 56, the inside diameter of the tubular member being considerably greater than the outside diameter of member 56.

The inside surface of the sleeve 108 is provided with a plurality of inclined vanes 110 extending toward and sliding on the surface of the tubular member 56, the vanes being provided for the purpose of effecting an intermittent rotary movement of the valve, due to the oil flowing through the space between the tubular member 56 and plate valve, in order to secure a cleaning action on the contacting surfaces of the valve and valve seating surface.

It will be seen from the above described construction that the operating mechanism for the pump comprises essentially a single barrel divided into upper and lower compartments, the operating fluid, either liquid or gas, being introduced into the lower compartment by the construction insuring that it cannot enter the upper compartment except after having raised the piston 60 to the upper end of its stroke. By this simplified construction, sufficient space is provided for the various passages and valves controlling them so that the passages and working parts can be made of substantial size, both to secure adequate strength, reduce friction, and to avoid the danger, present in small diameter passages, and becoming clogged with sand or other matter.

The operation of the pump mechanism will now be described. Before fluid pressure is applied to the operating mechanism, the operating piston 60 will be at the lower end of its stroke and the valves 68 controlling the passages 78 through the piston 60 will have been closed by engagement with the spring 86. The reciprocating pump piston 96 will have a column of oil within pump cylinder 94 standing above the traveling valve 100 and the interior of the barrel 10 will be filled with the oil. On the admission of fluid under pressure through the inner tube 54, operating fluid will pass through tube 62 and through passage 66 to the space below operating piston 60 forcing the piston to move upwardly and holding closed the mushroom valves 68, thus moving reciprocating pump piston 96 to the top of its stroke and drawing a fresh charge of oil into the pump cylinder 94 through the standing valve 98.

Shortly before the operating piston 60 reaches its uppermost position, the projecting stems 70 of the valves 68 will strike the undersurface of the partition 58, causing the valves 68 to snap open against the pressure of the gas below the piston, the movement being aided by the effort of the springs 76. The fluid under pressure will then flow through the passages 78 in the piston 60, into the space between the tubular member 56 and the wall of the barrel 10 and will pass upwardly between the outer surface of the tube 54 and the inner surface of the tube 24 through the standard packer 13 and outwardly through the bore 15 at the top of the standard packer into the space between the tube 24 and the well casing 12 and will flow out of the top of the well.

The oil which is displaced from above the operating piston 60 on its upward stroke will flow through the passages 57 through the partition 58, raising the valve 59 from its seat, rotating it to a greater or lesser degree, and passing into

the same space as that into which the working fluid, either liquid or gas under pressure, is exhausted. If a gaseous working fluid is used, the exhaust gas will aerate the oil, thereby accelerating its upward movement.

When the pressure is removed from the operating fluid by the mechanism at the surface, the pump operating parts will sink to their initial position by gravity, the valves 68 remaining open during a portion of the down stroke to permit oil below the piston 60 to pass through passages 78 to the upper surface of the piston 60, the oil trapped in the pump reciprocating cylinder above the standing valve 98 moving through the path provided through the lower end of the piston rod 80 to the space above the reciprocating pump piston 96.

It is pointed out that by providing valve rods 70 of different lengths, the suddenness with which the gas below the piston 60 is released may be adjusted, thus providing a desirable degree of adjustment for different heads against which the pump must be able to work.

It will be noted that the parts are relatively few in number and simple in construction, insuring low cost of manufacture and of maintenance.

The invention has been described and illustrated in a preferred form, but it is to be understood that the scope of the invention is not in any way limited by this illustrative showing but only as indicated by the scope of the appended claims.

I claim:

1. In well pumping apparatus having means for intermittently supplying working fluid under pressure, a barrel for mounting in the well, a partition dividing the barrel into an upper compartment and a lower compartment, a port in the partition, a non-return valve controlling said port, a working fluid actuated piston reciprocably mounted in the lower compartment, a first conduit fixed in the barrel and adapted at its top end for communication with the pressure means, a second conduit fixed at its bottom end to the piston and having its top end reciprocably fitting in the lower end of the first conduit whereby to deliver working fluid under pressure to the lower compartment below said piston, a discharge port through the piston, a check valve seating in said discharge port towards the upper compartment, means for unseating the check valve in response to predetermined upward movement of the piston, a pump connected to said piston for drawing fluid from the well into said lower compartment below said piston upon movement of said piston upwardly, means for trapping fluid from the well in the lower compartment below the piston upon downward movement of said piston, and means for passing fluid from the upper compartment.

2. In well pumping apparatus having pressure means for intermittently supplying working fluid under pressure, a barrel for mounting in the well, a partition dividing the barrel into an upper compartment and a lower compartment, a port in the partition, a non-return valve controlling said port, a fluid actuated piston reciprocably mounted in the lower compartment, a first conduit fixed in the barrel and adapted at its top end for communication with the pressure means, a second conduit fixed at its bottom end to the piston and having its top end reciprocably fitting in the lower end of the first conduit whereby to deliver working fluid under pressure to the lower com-

partment below said piston, a discharge port through the piston, a check valve seating in said discharge port towards the upper compartment, conduit means for conducting spent working fluid and well fluid from said upper compartment to the surface of the ground, a cylinder carried by the lower end of the barrel, an inlet port in the lower end portion of the cylinder, a check valve seating in said port towards the well, a pump piston reciprocably mounted in the cylinder above said inlet port, rod means operatively connecting the pump piston to the fluid actuated piston, a port in the pump piston for passing fluid upwardly through the pump piston during downward movement of the pump piston and valve means in said last named port for preventing return flow of said well fluid.

3. In well pumping apparatus having pressure means for intermittently supplying working fluid under pressure, a barrel for mounting in the well, a partition dividing the barrel into an upper compartment and a lower compartment, a port in the partition, a non-return valve controlling said port and preventing downward movement of fluid therethrough, a fluid actuated piston reciprocably mounted in the lower compartment, a first conduit fixed in the barrel and adapted at its top end for communication with the pressure means, a second conduit fixed at its bottom end to the piston and having its top end reciprocably fitting in the lower end of the first conduit whereby to deliver working fluid under pressure to the lower compartment below said piston, a pair of discharge ports through the piston, a check valve controlling each port and seating towards the upper compartment, a pair of valve opening stems connected at their lower ends to the respective check valves and projecting at their top ends from the top of the piston for abutment against the partition, one of said stems projecting further from the piston than the other, a pump connected to said piston for drawing fluid from the well into said lower compartment below said piston upon movement of said piston upwardly, means for trapping fluid from the well in the lower compartment below the piston and means for passing spent working fluid and well fluid from the upper compartment.

4. In well pumping apparatus having pressure means for intermittently supplying working fluid under pressure, a barrel for mounting in the well, a partition dividing the barrel into an upper compartment and a lower compartment, a port in the partition, a non-return valve controlling said port, a fluid actuated piston reciprocably mounted in the lower compartment, a first conduit fixed in the barrel and adapted at its top end for communication with the pressure means, a second conduit fixed at its bottom end to the piston and having its top end reciprocably fitting in the lower end of the first conduit whereby to deliver fluid under pressure to the lower compartment below said piston, a discharge port through the piston, a check valve seating in said discharge port towards the upper compartment, means for unseating the check valve in response to predetermined upward movement of the piston, means for introducing well fluid into the lower compartment below the piston in response to upward movement of the piston and means for passing spent working fluid and well fluid from the upper compartment.

5. In well pumping apparatus having pressure means for intermittently supplying working fluid under pressure; a barrel adapted to be mounted

in the well; a partition dividing said barrel into an upper compartment and a lower compartment; outlet ports in said partition and non-return valve means controlling said outlet ports; an operating piston reciprocably mounted in said barrel below said partition; conduit means providing fluid communication from the pressure means to the lower compartment through the piston; a port communicating between the lower face and upper face of the operating piston; a valve controlling the passage of fluid through said port; a piston rod secured to said piston and extending downwardly therefrom; a pump cylinder secured to the bottom of said barrel; a pump piston working within said pump cylinder and mounted on the lower end of said piston rod; a traveling valve controlling the flow of well fluid from the pump cylinder below said pump piston into said barrel; a standing valve arranged in the bottom of the pump cylinder; and conduit means for conducting exhausted working fluid and well fluid to the surface of the ground.

6. In well pumping apparatus having pressure means for intermittently supplying working fluid under pressure, a barrel for mounting in the well, said barrel having a well fluid inlet in its bottom end and a fluid outlet in its top end, a non-return valve controlling said inlet, an operating piston reciprocably mounted in the barrel, a pump connected to said piston for drawing fluid from the well into said barrel below said piston upon upward movement of said piston, a valve-controlled port in the piston for passing spent working fluid and well fluid through the piston at the upper end of its upward stroke and during downward movement of the piston, means for trapping said fluid passed through the piston above the piston against return flow, conduit means for conducting said trapped fluid to the surface of the ground, and telescopic conduit means for passing working fluid under pressure from the pressure means to the barrel below the piston, said conduit means extending through the piston.

7. In well pumping apparatus having pressure means for intermittently supplying working fluid under pressure, a well tubing communicating with said pressure means at its upper end, a barrel mounted at the lower end of said tubing and open thereto, a partition in said barrel, said partition having an opening therethrough, upwardly opening check valve means controlling said opening, a piston in said barrel, a valve-controlled port in the piston for passing fluid upwardly through the piston at the upper end of

its upward stroke and during downward movement thereof, a first conduit mounted in said barrel and extending upwardly inside said tubing for a limited distance providing a space between the tubing and said first conduit, packing means sealing off said space at a point above said barrel, said tubing having a discharge opening in its wall at a point between said barrel and said packing means, a second conduit mounted at its lower end in said piston and extending upwardly into the lower end of said first conduit and reciprocably fitting therein, the lower end of said second conduit being in communication with the under side of said piston whereby to deliver working fluid below the piston, and means for drawing well fluid into the lower end of said barrel and for trapping the same therein.

8. In well pumping apparatus having pressure means for intermittently supplying working fluid under pressure, a well tubing communicating with said pressure means at its upper end, a barrel mounted at the lower end of said tubing and open thereto, a piston in said barrel, a valve controlled port in the piston for passing fluid upwardly through the piston at the upper end of its upward stroke and during downward movement thereof, means for trapping fluid passed through the piston against return flow, a first conduit mounted in said barrel and extending upwardly inside said tubing for a limited distance providing a space between the tubing and said first conduit, packing means sealing off said space at a point above said barrel, said tubing having a discharge opening in its wall at a point between said barrel and said packing means, a second conduit mounted at its lower end in said piston and extending upwardly into the lower end of said first conduit and reciprocably fitting therein, the lower end of said second conduit being in communication with the under side of said piston whereby to deliver working fluid below the piston, and means for drawing well fluid into the lower end of said barrel and for trapping the same therein.
